UNITED STATES PATENT OFFICE.

THOMAS D. FINIZIO, OF KITCHAWAN, NEW YORK, ASSIGNOR OF TWO-THIRDS TO
HAROLD C. BIGLIN AND LESTER E. MOFFATT, BOTH OF NEW YORK, N. Y.

INVERTED-LAMP SHADE-HOLDER.

1,249,364.

Specification of Letters Patent. Patented Dec. 11, 1917.

Application filed September 15, 1916. Serial No. 120,219.

To all whom it may concern:

Be it known that I, THOMAS D. FINIZIO, a subject of the King of Italy, residing in the town of Kitchawan, in the county of West-
5 chester and State of New York, have invented certain new and useful Improvements in Inverted-Lamp Shade-Holders, of which the following is a full, clear, and exact description, such as will enable others skilled
10 in the art to which it pertains to make, construct, and use the same, reference being had to the accompanying drawings, and to numerals of reference marked thereon, forming a part of this specification.

15 My invention relates to improvements in the construction of shade holders for attaching and supporting preferably dome-shaped lamp shades, from an incandescent electric lamp. The lamp shade, which may be made
20 of glass or any other suitable material, is preferably provided with an outwardly extending circumferential bead to receive the lower portion of the shade holder, thereby maintaining the holder in its proper position
25 thereon, the upper portion of the holder being provided with two portions bent to form resilient members adapted to contact with the globe of said lamp and for conveniently inserting the globe of the lamp
30 between said resilient members, the whole being constructed and arranged as to be hereinafter described, and forming an inexpensive, simple and efficient holder for the purpose described.

35 While the preferred form of my invention is illustrated in the accompanying drawings, yet it is to be understood that minor changes may be made without departing from the scope thereof.

40 In the accompanying drawings,

Figure 1 represents a side elevation of my improved lamp shade holder, upon an incandescent lamp.

Fig. 2 represents a plan view of the shade holder removed from the shade, but applied to the lamp.

Fig. 3 represents a plan view of the shade holder; and

Fig. 4 represents a fragmentary sectional view of the shade and shade holder, illustrating the manner in which the shade holder is secured in the bead formed on the shade.

Similar characters of reference designate like parts throughout the different views of
55 the drawings.

In the drawing, 1 represents an incandescent electric lamp of the usual form and 2 represents a dome-shaped lamp shade made of glass or other suitable material and provided along its circumferential edge with an outwardly extending bead 3 to receive the lower portion of the shade holder 4.

The shade holder 4 is preferably made from a single piece of wire, or other suitable
60 material, bent to provide a central portion 5 of approximately semi-circular form to fit the inside of the outwardly extending bead 3 of the lamp shade 2 and by means of which said lamp shade is supported on the central
65 portion 5 of the shade holder 4. The central portion 5 of said holder 4 is provided with two return portions 6-6 lying approximately parallel with a portion of said central portion 5 and from which portions extend inwardly and upwardly toward each other spring members 7-7 each terminating
70 in a resilient or yielding loop 8, each loop designed to contact with the globe of the lamp, thereby supporting the shade holder
75 4 with its attached lamp shade 2 on the incandescent electric lamp 1.

It will be evident without further description that my improved shade holder is inexpensive and simple as regards construction
80 and that it effectually accomplishes the desired end.

Having thus described my invention, what I desire to claim and secure by Letters Patent is:-

1. A holder for supporting a shade on an incandescent electric lamp made from a single piece of suitable material bent so as to provide attaching means whereby the holder is removably secured to the circumferential edge of the lamp shade, diametrically-opposed resilient means extending inwardly and upwardly from said attaching means, said resilient means terminating in yielding means arranged in the same plane to each other and adapted to contact with and be frictionally secured to the globe of the lamp.

2. A holder for supporting a shade on an incandescent electric lamp made from a single piece of suitable material bent so as to provide an approximately semi-circular por-

tion, spring members extending at an angle to the plane of said semi-circular portion, connected to the semi-circular portion by return portions lying approximately parallel 5 with a portion of the said semi-circular portion, said spring members terminating in yielding loops arranged in close proximity to each other and adapted to contact with and be frictionally secured to the globe of 10 the lamp.

3. As a new article of manufacture, a lamp shade comprising a shade having an internal, annular groove, and a holder therefor consisting of a piece of wire bent at its middle 15 to form a base portion of circular form adapted to be sprung into said groove, the ends of said wire extending transversely of said base portion and being bent to form

gripping members capable of gripping an object therebetween.

4. As a new article of manufacture, a shade member having a central opening and an internal, annular groove, and a holder therefor consisting of a piece of wire bent at its middle into circular form to provide a 25 base portion adapted to seat in said groove, the end portions of the wire being bent to lie in planes transversely of the base portion and having curved ends adapted to grip an object therebetween.

This specification signed and witnessed this 7th day of September, 1916.

THOMAS D. FINIZIO.
